CLAIM

The ornamental design for a wheelbarrow stabilizer support as shown and described.

DESCRIPTION

FIG. 1 is a top, back, left side perspective view of a wheelbarrow stabilizer support.

FIG. 2 front elevation view thereof.

FIG. 3 is a back elevation view thereof.

FIG. 4 is a left side elevation view thereof.

FIG. 5 is a right side elevation view thereof.

FIG. 6 is a top view thereof.

FIG. 7 is a bottom view thereof.

FIG. 8 is a top, back, left side perspective view of a wheelbarrow stabilizer support shown in a condition of use; and,

FIG. 9 is a bottom, front, left side perspective view of a wheelbarrow stabilizer support shown in a condition of use. The features shown in broken lines in the drawing depict portions of the wheelbarrow stabilizer support and form no part of the claimed design. The broken lines depicting a wheelbarrow in FIGS. 8 and 9 depict environment and form no part of the claimed design.

1 Claim, 7 Drawing Sheets
